UNITED STATES PATENT OFFICE.

JEROME C. TAYLOR, OF HUNTINGTON BEACH, CALIFORNIA.

OIL-WELL-TUBING DRAINER.

Application filed April 22, 1926. Serial No. 103,813.

My invention relates to an oil well tubing drainer, that will permit the draining of the contents of a string of oil well tubing while in the well, in which invention or device the 5 valve consists of plungers and plunger bores operated in conjunction with and opened automatically by a spring mandrel guide assembly; the said valve being opened and closed by the withdrawing and inserting of 10 said plungers in their bores past channels or openings leading from the inside to the outside of the tubing which openings are intercepted by the plungers when inserted in their bores; and the object of the device is 15 to provide a means of automatically draining the contents of a string of oil well tubing as and before the said tubing is removed from the well.

I attain these objects by means of the 20 mechanical device illustrated in the accompanying drawing, in which:—

Figure 1 is a view in perspective of said 25 mechanical device in actual use, incorporated into a string of tubing which has been lowered into the casing, showing the top half of a part of the casing removed.

Figure 2 is a vertical cross section of the 30 device on the dotted line 1, 2 in Figure 3.

Figure 3 shows a view of the drain block 35 (c) looking down from above when the device is in a vertical position.

Figure 4 is a cross section of the drain block (c) plungers (p) and plunger block (d) on the dotted line 1, 2 in Figure 3, 40 showing the plungers withdrawn in their bores past the channels or openings through which the contents of the tubing may pass out.

Similar letters refer to similar parts 45 throughout the several views.

The said tubing draining device consists and is made up of the following and in the following manner:—(b) is a steel tube both ends of which are threaded with standard 50 male threading. (c) is a drain block made by taking a parallelepiped rectangular solid block of steel and truncating the four longer edges so that the two square faces forming what will be termed the base and top are shaped as shown in Figure 3. Lengthwise through the center of the drain block a cylindrical bore (t) is drilled of about the same diameter as the outside diameter of the tube (b) the two ends of this bore being threaded to receive standard male threading as found on the ends of the tube 55

(b); also lengthwise through said drain block and in opposite corners thereof in the place indicated in the accompanying drawing two other cylindrical bores of smaller 60 diameter (o) are bored. The said three bores being parallel with each other and the longer sides and edges of the truncated parallelepiped drain block (c). The two smaller bores (o) will hereafter be referred 65 to as plunger bores. Each of said plunger bores is connected with the larger bore (t) by cylindrical channels (n) bored at right angles to the said plunger bores (o). At another point in the plunger bores (o) each 70 of said plunger bores (o) is also connected with the outside of the drain block (c) by two cylindrical channels or holes (m) bored through said drain block at right angles to said plunger bores. 75

When the plungers (p) are withdrawn in their bores (o) past all of said holes or passages leading at right angles to them a passage or channel is opened leading from the inside of the bore (t) in the drain block 80 (c) through the drain block (c) to the outside thereof the course of which may be seen by referring to the course marked by the arrows in Figure 4 of the drawing.

When the plungers (p) are fully inserted 85 in their bores (o) past all of said holes or passages (n and m) the opening or channel or passage leading from the inside of the larger bore (t) out through the drain block (c) and to the outside thereof are all closed. 90

The drain block (c) is fastened to one end 95 of the tube (b) by means of the aforementioned threading, that is by screwing the male threading on one end of the tube (b) into the threading on the inside of the bore (t). The tube (b) and drain block (c) thus assembled form the frame of the device. Just above the threading on the end of the tubing (b) opposite the drain block a coil 100 spring retainer (i) is welded.

Closely fitted over the tube (b) is a second tube (e) of somewhat shorter length, hereinafter referred to as the plunger block sleeve, which slips up and down on said tube (b). This second tube (e) is also fitted 105 with standard male threading on both ends, one end of which is screwed into a collar (h) and the other end is screwed into a square collar with truncated lateral edges (d) hereinafter referred to as the plunger block and from which plunger block projects two cylindrical columns (p) hereinafter 110

called plungers so placed as to slide up and down in the plunger bores (o) into which they are closely fitted, as the plunger block sleeve (e) slips up and down on the tube (b).

5 A coil spring (s) is fitted around the tube (b) one end of which spring rests in the coil spring retainer (i) and the other end against the collar (h) with sufficient tension to hold the plunger block (d) against the drain block (c) and causing the plungers (p) to be fully inserted in their plunger bores (o). If force is applied to the plunger block sleeve (e) it may be forced down against the said coil spring compressing it 10 and allowing the plunger block sleeve to slide down away from the drain block (c) and drawing the plungers (p) downward in their bores (o).

20 The tension of the coil spring (s) may be increased or lessened by introducing a longer or shorter spring tension spacer (j) between the coil spring (s) and the bottom of the coil spring retainer (i).

25 The open ends of the plunger bores (o) opposite the ends where the plungers enter are closed by inserting therein pipe plugs (l) but a very small hole is drilled through these pipe plugs which permits the intake and escape of air or liquid from the plunger 30 bores when the plungers are withdrawn and inserted in said plunger bores.

35 Sliding up and down on the plunger block sleeve (e) between the plunger block (d) and the collar (h) is a spring mandrel guide assembly consisting of four convex springs (g) fastened at each end to a spring mandrel guide ring (f) by means of cap screws (r). The spring mandrel guide assembly is of sufficient size and so constructed that the 40 spring mandrel guide springs (g) make contact with the inside of the well casing into which the said draining device is inserted when in use.

45 The size of the various parts above referred to must of necessity vary with the size of the casing in which the drainer is to be used. For example if the drainer is to be used in a string of 6 inch well casing the inventor has used the following size parts, 50 to-wit:—The tube (b) is approximately six feet long and two and a half inches in diameter (inside measurement) and is made of standard two and a half inch oil well tubing. The plunger block sleeve (e) is made of 55 standard three inch oil well tubing and is about four feet long and three inches in diameter (inside measurement). The drain block (c) is approximately $4\frac{3}{8}$ inches by $4\frac{3}{8}$ inches by 6 inches. The plunger bores (o) 60 are $\frac{5}{8}$ inch in diameter. The spring mandrel guide is approximately 10 inches long.

The method of using and operating the tubing draining device is as follows:—

65 The tubing drainer is incorporated into the string of tubing to be lowered into the

well and forms an integral part thereof, by coupling the same with the drain block (c) up, by means of threading, between two lengths of the tubing forming the string of tubing to be lowered as aforesaid, as shown 70 in Figure 1 in the accompanying drawing. As the string of tubing into which the draining device has been incorporated as aforesaid is lowered into the casing the spring mandrel guide assembly engages and forms 75 a friction contact with the inside of the casing slipping only with some pressure. This friction causes the spring mandrel guide assembly to be forced up against the plunger block (d) as the tubing is lowered or forced 80 down in the casing. The pump or other means of forcing up the oil is started and the oil is drawn up through the tubing in the usual way, which usual way is through a valve at the bottom of the tubing. 85

If it is desired to pull the string of tubing out of the well and no such tubing drainer as here above described is incorporated into the string of tubing the tubing remains full of oil as it is taken from the casing and as 90 the joints are unscrewed the oil therein spills out promiscuously and is wasted and lost as it cannot be conveniently caught or saved. It therefore becomes desirable to drain the tubing while it is in the casing thus saving 95 the oil. If the string of tubing has incorporated into it the tubing draining device above described all that is necessary to do to drain the tubing while in the casing is to start to pull out the string of tubing. As the 100 string of tubing starts upward the spring mandrel guide assembly sticks to the inside of the casing on account of the spring contact therewith and the plunger block sleeve (e) slides up through it until the collar (h) 105 thereon comes in contact with said spring mandrel guide assembly whereupon the friction drag or pull of the spring mandrel guide is exerted against the collar (h) causing the plunger block sleeve (e) and 110 plunger block (d) carrying the plungers (p) to travel downward towards the coil spring retainer (i) and the plunger block (d) to travel away from the drain block (c) withdrawing the plungers in their bores past all 115 of the passages or openings (n and m) thus affording the oil or contents of the string of tubing a passage way or means of escape through the drain block and into the well casing in the manner indicated by the arrows in Figure 4 of the accompanying drawing, thus draining the string of tubing. 120

It will be observed that the tubing drainer is automatically operated and opened and the tubing drained when the string of tubing 125 is started to be withdrawn from the well.

With respect to said device and invention, I claim:—

1. The combination with a pump tube, of a normally closed drainage valve mounted in 130

the pump tube, a friction device slidably mounted upon the pump tube and adapted to engage a well casing in which the tube is inserted, means limiting the sliding movement of said friction device relatively upward on the pump tube, a member engaged by said friction device upon a relatively upward movement of the pump tube causing the opening of said valve, and a spring normally engaging said member to resist the movement thereof.

2. The combination with a pump tube, of a valve block having a main bore extending therethrough for threadedly receiving one end of the pump tube, a pair of auxiliary bores, a pair of transverse bores connecting the main bore and the auxiliary bores and a

second pair of transverse bores connecting the auxiliary bores with the exterior of the block, means for closing the upper ends of the auxiliary bores, plungers slideable in the auxiliary bores, a head slideable on the tube and connected with the plungers, a suction device slidably mounted upon the front tube and adapted to engage a well casing in which the tube is inserted, said device adapted to engage the plunger head upon the downward movement of the tube in the casing and means engaged by said friction device upon a relatively upward movement of the front tube causing the downward movement of the head with its plungers for opening the valve formed by the block and plungers.

JEROME C. TAYLOR.
